[57] **CLAIM**

The ornamental design for a handle for culinary tools or
the like, as shown and described.

DESCRIPTION

FIG. 1 is a side elevational view of a handle for culinary
tools or the like showing our new design;

FIG. 2 is an end elevational view thereof as seen from
line 2—2 of FIG. 1; and

FIG. 3 is an end elevational view thereof as seen from
line 3—3 of FIG. 1.

The top and bottom are similar in configuration to the
side with the opening omitted.

FIG.1

FIG.2

FIG.3
